CLAIM

(21) Appl. No.: **29/339,197**

The ornamental design for a three-dimensional hexagonal presentation device, as shown and described.

(22) Filed: **Jun. 25, 2009**

DESCRIPTION

Related U.S. Application Data

(63) Continuation-in-part of application No. 11/522,202, filed on Sep. 15, 2006.

The three-dimensional hexagonal device of the present invention has an ornamental design used to present information and images. Accessory items can be attached to the claimed device, and examples include a note pad, a sample, a gift card, and a business card.

(51) **LOC (9) Cl.** **19-07**

FIG. 1 is a perspective frontal view of the present invention with flaps partially opened.

(52) **U.S. Cl.** **D19/62; D20/10**

FIG. 2 is a frontal view of the present invention with flaps opened.

(58) **Field of Classification Search** D19/2, D19/6, 20-25, 29, 59-64; D9/420, 430-433, D9/501; D11/141; D20/10, 29, 43; D21/714; 40/107, 119; 211/72; 229/114, 938; 281/2, 281/5, 51; 283/2, 34; 428/7; 434/135, 137, 434/150, 403; 493/116

FIG. 3 is a back view of the present invention with flaps opened.

See application file for complete search history.

FIG. 4 is a side view of the present invention with flaps opened.
